PATTERN CONTROLLED DUPLICATING
MACHINE

Paul C. Hougham, Visalia, Calif.

Application February 14, 1949, Serial No. 76,348

7 Claims. (Cl. 144—144)

1

My invention relates to a duplicating machine for making bow staves.

One of the principal objects of this invention is to provide a duplicating machine of this class which is so designed that it will accurately duplicate not only the different length limbs of a bow stave but also staves of different lengths and shapes.

Another important object of this invention is to provide a machine which may be quickly and easily adjusted for making staves of various lengths, and also a machine which may be readily operated.

An important object of this invention also is to provide novel and simple means for flexibly holding either or both the pattern and bow stave, or other element, during fabrication of the latter.

A novel feature of this invention is to provide a movable carriage for supporting one end of the pattern or element to be fabricated, or both, for feeding the same longitudinally, and roller means for supporting the opposite end or ends of the pattern, or element, or both during such movement.

Still another important object of this invention is the provision of a roller for supporting the free end of the bow stave, or other element, which may be readily adjusted transversely with respect to the guiding face of a pattern so that the thickness of the stave, or other element, may be readily varied.

A further important object of this invention is to provide a novelly constructed and operable head carrying a cutter movable directly responsive to the contour of the desired pattern.

Another important object of this invention is to provide a novel and simple tiller or bow pattern, for a machine of this class, which may be easily and quickly adjusted.

With these and other objects in view, as will appear hereinafter, I have devised a duplicating machine having certain novel features of construction, combination, and arrangement of parts and portions, as will be hereinafter described in detail, and particularly set forth in the appended claims, reference being had to the accompanying drawings and to the characters of reference thereon, which form a part of this application, in which:

Fig. 1 is a plan view of my duplicating machine;

Fig. 2 is a side elevational view of the same;

Figs. 3, 4, and 5 are cross-sectional views, respectively, taken on lines 3—3, 4—4, and 5—5 of Fig. 1;

2

Fig. 6 is a plan view of the side guides for the free end of the bow stave;

Fig. 7 is an enlarged fragmentary side view of the adjustable pattern or tiller, showing it adjusted for fabricating the top portion or limb of the bow stave;

Fig. 8 is a view similar to Fig. 7, showing the pattern adjusted for cutting the bottom limb of the bow stave; and,

Fig. 9 is a cross-sectional view, taken on line 9—9 of Fig. 7.

Referring to the drawings in detail, my improved duplicating machine comprises a bed 10 constructed from channel irons 11 and provided with an extension 12 at its rearward end. Mounted in cross-members 13 and 14 of the bed 10 are forward and rearward antifriction bearings 15 and 16 which rotatably support a longitudinal feed screw 17. The forward projecting end of the screw 17 carries a gear 18 by which the screw can be driven at a relatively slow speed from any suitable prime mover, such as an electric motor, not herein shown. Secured to the extension 12 are support brackets 19 which carry transverse pins 20 for pivotally supporting a tiltable head 22. Mounted on the head 22 is an electric motor 23 having a pulley 24 connected to its shaft.

The tiltable head 22 has depending bearing ears 26 at its forward end, the ears carrying antifriction bearings 27 for rotatably supporting a cutter mandrel 28. As shown in Fig. 3, the mandrel 28 is retained axially in place by a collar 29 at one end and by a V-belt pulley 30 at the other end, the pulley being adapted to be driven from the pulley 24 by means of a belt 31. The mandrel 28 carries a rotary cutter element 33 substantially midway between the ears 26, and rollers 34 and 35 disposed at the sides of the cutter element.

The rotary cutter element 33 is adapted to cut the upper edge or back side of a long strip S of wood to form, for example, an archer's bow. As is well known, an archer's bow consists of a long strip of highly flexible wood provided with a substantially central handle portion or grip, the strip tapering from the grip portion toward the ends of the bow, that portion of the bow which extends upwardly from the grip being termed the top limb and that portion below the grip being called the bottom limb of the bow. Since the arrow is shot from above the midpoint of the bow, the supporting hand of the archer must be disposed partially below the center of the bow. Consequently, in some instances, it is necessary to arrange the widened

grip portion "off center," that is, slightly below the center of the bow. The present duplicating machine is designed to cut a bow stave to such configuration in the manner to be later explained.

The strip S of wood from which the bow is to be fabricated is connected, at its midpoint, to a carriage 40 which, as shown in Fig. 5, is provided with lateral grooves for receiving longitudinal guides 41 of the bed 10 so as to adapt the carriage to slide longitudinally thereof. The carriage 40 has jaws 42 which are adapted to embrace the feed screw 17 to be fed thereby longitudinally along the bed, the jaws being drawn together to engage the screw by handle-operated means indicated at 43. Carried by the slideable carriage 40 is a holder 45, between the upright sides of which is pivotally mounted, on adjustable studs 46, a U-shaped frame 47 upon which the midportion of the strip S rests (Fig. 5). Clamps 48 are pivotally mounted on the studs 46 and are adapted to be moved toward each other to grip the strip S therebetween. By this mounting means the strip S is held longitudinally, but permitted to pivot on the aligned studs 46 for the purpose to be hereinafter explained.

During the cutting operation, the strip S underlies the cutter element 33 and is cut or planed thereby as the strip is drawn longitudinally therebeneath. During this movement the strip S is held centrally of the bed 10 and cutter element 33 by means to be next described. Disposed just forwardly of the cutter element 33 is a cross-member 48 to which is pivoted a pair of arms 49 carrying rollers 50 at their free ends. A slide element 51 is slideable longitudinally of the cross-member 48, and pivotally connected between the slide element and the free ends of the arms 49 are links 52. A spring 53 compressed between a lug on the cross-element 48 and the slide element 51 normally slides the latter in a direction to cause the links 52 to draw the rollers 50 toward each other to grip the sides of the wooden strip S which, as shown in Fig. 1, may taper toward its ends. Thus, the strip is retained centrally of the cutter element 33, see Figs. 4 and 5.

Extending between the sides of the bed extension 12 is a support 55 which is provided with a vertical bearing 56 disposed beneath the cutter element 33. Adjustable vertically in the bearing 56 is a post 57. Between the sides of its upper forked end is rotatably mounted, on a cross-pin 58, a roller 60 which supports the free end of the strip S and maintains it in position to be engaged by the cutter element 33. The roller 60 can be adjusted vertically by moving the post 57 in the bearing 56 and retaining the post in adjusted position by a set screw 61 (Fig. 3), the post being moved vertically by means of a manually-operated screw 60' and held against rotation by a key 61'. As shown in Fig. 2, the head 22 is normally pivoted by gravity in counterclockwise direction to maintain the cutter element 33 in position to perform the cutting operation and this action may be augmented by a spring 62 connected between the head and the extension 12. However, the head 22 can be tilted upwardly, as indicated by dash lines in Fig. 2, to facilitate placing the strip S in the machine.

It is also desirable to press the work-piece S downwardly against the supporting roller 60 so as to prevent chattering of the strip being cut, and this is accomplished by means of a roller 65 rotatably mounted at the lower square end of a

spindle 66. The spindle 66 is slideable vertically on a transverse holder 67 whose ends are connected to upright brackets 68 mounted on the bed extension 12 by pins 69. A pair of rods 70 project upwardly from the holder 67 and carry a cross-bar 71 at their upper ends, the spindle 66 projecting upwardly through a hole in the cross-bar. A spring 72 is compressed between the cross-bar 71 and a collar 73 on the spindle and functions to force the spindle downwardly to maintain the roller 65 in engagement with the upper edge of the strip S. By moving the cross-bar 71 vertically, the strength of the spring 72 can be readily adjusted, see Figs. 2 and 4. A cam disc 74 is eccentrically mounted on the spindle 66 and is adapted to engage the cross-bar 71, when rotated, so as to draw the spindle upwardly against the action of the spring 72 so as to elevate the roller 65 to facilitate placing the work-piece 5 therebeneath.

As previously pointed out, the strip S may be employed as an archer's bow, and when so formed in this machine it is provided with a central, relatively deep hand-grip portion and tapering end portions, the grip portion having curved edges connecting with the corresponding edges of the free end portions of the bow stave. To cause the rotary cutting element 33 to cut the strip S to the configuration just described, a pair of patterns 75 and 76 are employed. As shown in Figs. 2, 7, and 8, the patterns 75 and 76 each comprise an upper element 77 and a lower element 78. The upper element 77 consists of a substantially rectangular bar having a curved surface 79 at one end, which corresponds to the curved shape to be produced at the ends of the grip portion of the bow stave.

The lower edge of the upper element 77 is reduced in width to provide a tongue 80 which is adapted to be received in a longitudinal groove 81 of the lower element 78. The element 78 is provided with a series of transverse holes 82 which are adapted to align with similar holes in the tongue 80 of the element 77, and removable pins 83 inserted through aligned holes retain the two elements in selected longitudinally adjusted positions. The holes 82 are spaced apart in increments of, say, one-inch, and alongside each hole is a scale-marking so that the element 78 resembles a yardstick. The holes are adapted to be selectively aligned with index marks 85 or 85A on the upper element 77, these marks representing the center points of the various bow staves to be produced. An indicator finger 86 on the upper element 77 is adapted to register with a center mark inscribed at the center of the strip S, when the patterns 75 and 76 are mounted on the machine, as next explained.

Each upper element 77 has an aperture 87 for receiving a mounting pin 88 which is receivable in a hole in a projection of the holder 45 so as to connect the patterns 75 and 76 to the slideable carriage 40 for longitudinal movement therewith. The free end of each pattern 75 and 76 is supported by a grooved roller 90 (Fig. 3) mounted for rotation beneath one of the rollers 35 which rests upon the upper edge of a pattern. As will be apparent from the foregoing, the rollers 34 and 35, which rest upon the patterns 75 and 76, serve to raise and lower the head 22 and the cutter element 33 so as to cause the latter to cut the upper edge of the strip S to a shape corresponding to that of the patterns during longitudinal sliding movement of the carriage 40 from right to left, as viewed in Figs. 1

and 2. At the start of the cutting operation, the wide portion of each upper pattern element 17 is disposed beneath a roller 35 so that a corresponding deep grip portion is provided on the strip or stave S. As the operation progresses and the carriage moves toward the left, the rollers 34 and 35 ride down the inclined curved edges 19 and thus cause the cutter element to cut a corresponding curved portion at an end of the grip portion. Further movement of the carriage under the feeding action of the screw 17 causes the cutter element 33 to cut the upper edge of the free end of the stave S on a slope corresponding to that of the patterns.

While the patterns 15 and 16 might be made to conform to the shape of the entire bow stave to be fabricated, they are herein shown as made substantially equal to and of a shape corresponding to only one-half the bow stave. By this arrangement, the machine need be made only substantially equal to one-half the total length of the bow stave S. Assuming that the bow stave is to have a top limb which is one-half of 5'-10" from the center of the stave to its nock, the lower element 18 of each pattern 15 and 16 is adjusted longitudinally of the upper element 17 until the hole marked 5'-10" registers with the index mark 85 on the upper element 17, as shown in Fig. 7, whereafter pins 83 are inserted in appropriate aligned holes 82 to retain these parts in adjusted position. The wooden strip S is then placed in the machine and clamped in position between the clamps 48 on the carriage 40, the center of the proposed hand-grip of the stave being aligned with the indicator finger 86. The stave is inserted in the machine while the head 22 is in raised position, and after clamping the stave in place the head 22 is lowered until the rollers 34 and 35 rest upon the upper edges of the patterns 15 and 16.

At the start of the cutting operation, the point 90 (Figs. 2, 7, and 8) of the patterns are disposed beneath the rollers 34 and 35. To start the duplicating operation, the motor 23 is started to cause rotation of the cutter element 33, and the clamping means 43 is operated to operatively connect the carriage 40 to the rotating feed screw 17. By this means, the carriage is fed at a slow rate toward the left to draw the patterns 15 and 16 and the wooden strip S in the same direction. Thus, as the rollers 34 and 35 ride down the curved sloping edges 19 of the patterns, the cutter element 33 is caused to cut the strip S with a like curve, this curve forming an end of the grip portion. As the cutting operation progresses, the cutter element 33 planes the upper edge of the strip S along a line which corresponds to the gradual slope of the upper edges of the patterns.

At the completion of the shaping of the upper limb of the bow stave S, the stave is unclamped and reversed in the machine. When the bottom limb of the bow stave is to be shorter than the upper limb, as is quite common, the pins 83 are removed and the lower elements 18 slid to the left (Fig. 8) until the bottom 5'-10" hole 82 aligns with the index mark 85, after which the pins are reinserted, the center line of the stave S being aligned with the indicator finger 86, as before explained. Such relative adjustment of the parts 17 and 18 of the patterns automatically compensates for the difference in the length of the upper and lower limbs of the bow to be produced, if duplication of a bow of unequal limb length is the case, and thus the set-

ting up of the machine is greatly simplified and expedited. Likewise, if a bow having limbs of equal length is to be duplicated, the indicator arrow 85A is aligned with the hole indicating the proper length in the upper row of holes 82 so that both ends of the stave can be shaped without altering the pattern. During the cutting operation, the stave S can pivot on the studs 46. When the front side of a bow stave S is irregular, as is the case when the cut follows the grain of the wood, the back side cut in the present machine also follows this contour and yet is tapered in accordance with the patterns 15 and 16. To facilitate the placing of bow stave strips S having curved tips, the holder 67 can be pivoted upwardly on one of the pins 69 by first removing the other pin 69.

While the duplicating machine has been herein shown and described as embodied in a preferred form of construction, by way of example, it will be apparent that various modifications might be made in the construction without departing from the spirit of the invention. Consequently, I do not wish to be limited in this respect, but desire to be afforded the full scope of the following claims.

I claim:

1. In a duplicating machine of the class described, a bed, a carriage mounted to move longitudinally thereon, a pattern having one end only pivotally connected to the carriage, a readily releasable clamp means on the carriage including a pair of transversely adjustable studs having clamps pivoted on their inner ends and engageable against opposite sides of one end of the article to be duplicated for pivotally holding said end, a cutter head adjustably mounted on the bed and provided with a cutter rotatably mounted on an axis transverse to the longitudinal axis of the bed, vertically adjustable roller means for supporting the free end of the article pivotally held by the clamp means, the roller means being positioned on the bed below the cutter, a second roller means disposed below said cutter head for supporting the free end of the pattern, means in connection with the bed and the head for lowering the cutter on the article, and roller means on the head adapted to roll upon the pattern during longitudinal movement thereof so as to cause said cutter to follow the contour of the pattern.

2. In a duplicating machine of the class described, a bed, a carriage mounted to move longitudinally thereon, a pair of patterns each having an end pivotally connected to the carriage, one at the opposite sides of the longitudinal axis thereof, a pivoted clamp means on the carriage between the patterns for pivotally holding one end of the article to be duplicated, a cutter head adjustably mounted on the bed and provided with a cutter rotatably mounted on an axis transverse to the longitudinal axis of the bed, a first roller means for supporting the opposite free end of the article held by the clamp means, the first roller means being positioned on the bed below the cutter, a second roller means for supporting the free end of each pivoted pattern, means in connection with the bed and the head for lowering the cutter on the article, and roller means on the head adapted to roll upon the pattern during longitudinal movement thereof so as to cause said cutter to follow the contour of the pattern.

3. In a duplicating machine of the class described, a bed, a carriage mounted to move lon-

gitudinally thereon, a pattern having one end pivotally connected to the carriage, a pivoted clamp means on the carriage alongside the pattern for pivotally holding one end of the article to be duplicated, a cutter head adjustably mounted on the bed and provided with a cutter rotatably mounted on an axis transverse to the longitudinal axis of the bed, roller means for supporting the free ends of both the pattern and the article, a guide roller on the head disposed coaxially of said cutter, and means in connection with the bed and the head for lowering the cutter on the article, said roller resting upon the pattern to cause the cutter to follow the contour of the pattern.

4. In a duplicating machine of the class described, a bed, a carriage mounted to move longitudinally thereon, a pattern having one end pivotally connected to the carriage, a clamp means on the carriage, said clamp means having spaced pivotal jaws mounted to be adjusted toward and away from each other on an axis transverse to the longitudinal axis of the bed for pivotally holding one end of the article to be duplicated, a cutter head adjustably mounted on the bed and provided with a cutter rotatably mounted on an axis also transverse to the longitudinal axis of the bed, a first roller means for supporting the opposite free end of the article held by the clamp means, the first roller means being positioned on the bed below the cutter, means in connection with the bed and the head for lowering the cutter on the article, and a second roller means on the head disposed coaxially of said cutter and adapted to roll along the pattern during longitudinal movement thereof so as to cause said cutter to follow the contour of the pattern.

5. In a duplicating machine of the class described, a bed, a carriage mounted to move longitudinally thereon, a pattern having one end pivotally connected to the carriage, a pivoted clamp means on the carriage alongside the pattern for pivotally holding one end of the article to be duplicated, a cutter head adjustably mounted on the bed and provided with a cutter rotatably mounted on an axis transverse to the longitudinal axis of the bed, a pair of rollers mounted on axes also transverse to the longitudinal axis of the bed, both rollers being positioned substantially below the cutter, the free ends of both the pivoted pattern and the pivoted article each riding upon one of the rollers of said pair of rollers, means in connection with the bed and the head for lowering the cutter on the article, and follower roller means on said cutter head rollable along the pattern during longitudinal movement thereof so as to cause said cutter to follow the contour of the pattern.

6. In a duplicating machine of the class described, a bed, a carriage mounted to move lon-

gitudinally thereon, a pattern pivotally connected to the carriage, a pivoted clamp means on the carriage for pivotally holding one end of a flexible article to be duplicated, a cutter head adjustably mounted on the bed and provided with a cutter rotatably mounted on an axis transverse to the longitudinal axis of the bed, a first roller means for supporting the free end of the article held by the clamp means, the first roller means being positioned on the bed below the cutter, yieldable means for centering said opposite end of the flexible article on the roller means, means in connection with the bed and the head for lowering the cutter on the article, and a second roller means on the head adapted to roll along the pattern during longitudinal movement thereof so as to cause said cutter to follow the contour of the pattern.

7. In a duplicating machine of the class described, a bed, a carriage mounted to move longitudinally thereon, a pattern having one end pivotally connected to the carriage, a pivoted clamp means on the carriage alongside the pattern for pivotally holding one end of the article to be duplicated, a cutter head adjustably mounted on the bed and provided with a cutter rotatably mounted on an axis transverse to the longitudinal axis of the bed, a pair of rollers mounted on axes also transverse to the longitudinal axis of the bed, both rollers being positioned substantially below the cutter, the free ends of both the pattern and the article each riding upon one of the rollers of said pair of rollers, means for adjusting one of the rollers vertically with respect to the other, means in connection with the bed and the head for lowering the cutter on the article, and roller means on the head adapted to roll along the pattern directly above said roller which supports the pattern during longitudinal movement thereof so as to cause said cutter to follow the contour of the pattern.
